UNITED STATES PATENT OFFICE.

FRANK VOIGTMANN, OF CHICAGO, ILLINOIS, AND SILAS H. POMEROY,
OF NEW YORK, N. Y.

WINDOW.

SPECIFICATION forming part of Letters Patent No. 729,814, dated June 2, 1903.

Application filed September 30, 1902. Serial No. 125,421. (No model.)

To all whom it may concern:

Be it known that we, FRANK VOIGTMANN, residing at Chicago, Illinois, and SILAS H. POMEROY, residing at New York, State of New York, citizens of the United States, have invented certain new and useful Improvements in Sheet-Metal Windows, of which the following is a specification.

This invention relates to improvements in sheet-metal windows, and refers more specifically to a sheet-metal window-sash of improved construction.

The salient object of the invention is to provide a more simple and efficient construction which may be formed by machine and with the minimum number of operations, thereby greatly lessening the cost of production and at the same time producing a better-finished and more sightly construction.

20 A further object of the invention is to dispense with a large number of seams or joints which have heretofore been unavoidable in the construction of devices of this character, the dispensing with these joints or seams rendering the structure more perfect in its weatherproofing qualities, obviating entirely the necessity of soldering or otherwise sealing the joints, and at the same time providing a more durable and reliable structure.

30 Still further objects of the invention are to provide a construction in which the installation of the glazing, either originally or when it becomes necessary to renew the same, may be accomplished with the utmost facility and in which the several members of the sash or frame may be originally assembled with the minimum amount of labor, to provide a construction which is fireproof in the highest degree attainable in a sheet-metal construction, and in general to provide a simple and improved construction of the character referred to.

To the above ends the invention consists in the matters hereinafter described, and more particularly pointed out in the appended claims, and the same will be readily understood from the following description, reference being had to the accompanying drawings, in which—

50 Figure 1 is a face view of a window-sash

embodimenting our invention. Fig. 2 is a vertical sectional view taken on line 2 2 of Fig. 1. Fig. 3 is a horizontal sectional view taken on line 3 3 of Fig. 1, the central portion of the sash being broken out to reduce the size of the figure. Fig. 4 is a horizontal sectional view of one side of a sash of slightly-modified construction. Fig. 5 is a detail cross-sectional view of one side of one of the sash face members, showing more exactly the cross-sectional form of the same as it leaves the first forming-die; and Fig. 6 is a view similar to Fig. 5 of a modified construction.

Referring to said figures, 1 and 2 respectively designate as a whole front and back sash face members, which are desirably and, as shown herein, of similar construction, but reversely formed, so as to form a sash presenting a similar appearance on both sides. A salient feature of the present invention consists in forming the said sash face members 1 and 2 from single sheets of metal by means of suitable dies, so that all seams at the junctures of the side stiles with the top and bottom sash members are entirely obviated. Each sash face member is provided upon its inner margins with a die-formed molding or extension 3, which is struck up out of the general or face plane of the member and terminates at its inner edge 4 in a plane parallel with but considerably removed from the outer face plane. This molding-like extension is in cross-sectional form arranged to extend obliquely inwardly and toward the center of the sash, as indicated clearly in the several cross-sectional figures, and is desirably corrugated or ornamental-shaped, as indicated at 5, so that the glazing is recessed or set back from the face planes of the sash, as usual.

In the preferred construction illustrated in Figs. 1 to 3, inclusive, the inner margins of the face members are folded back upon themselves to form a double-thick flange portion 6 parallel with the outer face of the sash, the inner lap 7 of said double-thick portion being bent again at right angles to the general plane of the sash, as indicated at 8, to form the outer side of a channel, (designated as a whole 9,) which receives the edge of the glass 10. The two face members being similarly

but reversely formed are arranged with their double-thick flange portions 6 at a distance apart approximately equal to the thickness of the glazing and with their angular flange portions 8 overlapping, as indicated clearly in Fig. 3.

The outer marginal sides of the sash-frame are formed, in the preferred embodiment of the invention, of members 11, 12, and 13 of 10 channel shape in cross-section, the vertical side members 11 and the bottom member 12 being constructed to fit between the two face-plates with their lateral flange portions 11' and 12', respectively, directed outwardly and 15 terminating approximately flush with the margins of the face-plates. The face-plates are folded back or returned at their margins so as to embrace the edges of the channel-shaped members 11 and 12, as indicated clearly 20 at 14 and 15, respectively, thus forming at the margins of the sash flange-like extensions (designated as a whole 16 16' and 17 17') of three-ply strength. The top side member of the sash 13 is formed in the shape of a cap 25 which telescopes over the upper margins of the face-plates and is removably secured in place. To this end a filling-block 18 is fitted within the hollow top-rail thus formed, which filling-block is secured rigidly in position with 30 its upper surface flush with the top edges of the face-plates by means of screws inserted in said face-plates, as indicated in dotted lines at 19, and the cap member 13 is in turn secured to the filling-block by means of other screws, 35 as indicated in dotted lines at 20. The overlapping flange members 8, which form the outer sides of the glass-receiving channel or recess, are omitted across the top side of the sash, as best indicated in Fig. 2, so that when 40 the top cap 13 and filling-block 18 have been removed the glazing may be inserted in position. Fig. 5 shows a detail cross-sectional view of one of the stile members in the form in which it leaves the first pair of forming- 45 dies, the outer returned flange portion 14 or 15 being only partially bent to its final shape, and likewise the inner marginal portions 7 and 8 being but partially formed. By subsequent forming operations these parts are 50 formed into their final shape in a well-understood manner.

In Fig. 4 we have shown a slight modification, in which instead of forming the parts 7 and 8 of the glass-receiving channel integrally 55 with the face members a separate channel member 21 is provided, which is constructed to fit between the parallel flange portions 6' of the face members, and said channel member is provided with returned portions 22, which 60 embrace or are folded upon said flange portions 6'. In other respects the construction is or may be identical with that first described. The exact cross-sectional form of the face members shown in Fig. 4 is shown in detail 65 Fig. 6, it being understood that Fig. 6, like

Fig. 5, shows the face member in the form in which it leaves the first pair of forming-dies.

The assemblment of the several sash members is entirely obvious and need not, therefore, be described in detail.

It will be understood from the foregoing description that a sash-frame embodying our invention may be constructed in the most economical manner, since the die operations by which the chief members of the frame are 70 formed are extremely few and simple, and it will be further understood that a frame thus constructed is entirely free from external seams, which would tend to render the structure unsightly and are objectionable both because they must be sealed with solder to render the structure weatherproof and because they are expensive if riveted or clenched, so as to be fireproof. It will be noted that the construction is such that the sash-frame presents finished edges both around the glazing and its outer edges, thus not only enhancing the appearance of the frame, but rendering it smooth and capable of moving freely within the window-casing. It is still further to be 80 noted that a sash-frame made in accordance with the present invention is bound to be accurate as to its angles and finished form, thus obviating the inaccuracies due to handwork and to assembling a plurality of parts, which 85 as heretofore constructed have unavoidably been more or less inaccurate.

While we have shown and described herein what we deem to be a preferred embodiment of the invention, yet the details of construction may obviously be modified without departing from the spirit of the invention, and we do not, therefore, limit ourselves to the details of construction shown, except to such extent as they are made the subject of specific claims.

We claim as our invention—

1. In a sheet-metal window-sash, a sash face member struck up from a sheet of metal to form top, bottom and side stile members 100 integrally united and constituting one side of a sash-frame of circumferentially-uninterrupted continuity, the inner margins of said frame members being formed to extend to, and terminate in, a plane parallel with, but 110 removed from, the face plane of the sash, and channel-forming flange portions connected with said inner margins to receive the edge of the glass, substantially as described.

2. In a sheet-metal window-sash, a sash 120 face member struck up from a sheet of metal to form top, bottom and side stile members 110 integrally united and constituting one side of a sash-frame of circumferentially-uninterrupted continuity, the inner margins of said 125 frame members being formed to extend to, and terminate in, a plane parallel with, but removed from, the face plane of the sash, and channel-forming extensions formed integrally with said inner margins, said channel-form- 130

ing extensions comprising a returned portion arranged to extend parallel with the general plane of the sash, and a marginal portion bent at right angles to said returned portion, as and for the purpose set forth.

3. In a sheet-metal window-sash, the combination with a pair of reversely-formed sash face members, each struck up from a sheet of metal to form top, bottom and side stile members integrally united, the inner margins of said stile portions being formed to extend obliquely inwardly and toward each other and terminating in channel-forming portions, and top, bottom and side stile members formed independently of said face members, and extending between, and uniting the latter, at or near the outer margins thereof to form a hollow construction.

4. In a sheet-metal window-sash, the combination with a pair of reversely-formed sash face members, each struck up from a sheet of metal to form top, bottom and side stile members integrally united, the inner margins of said stile portions being formed to extend obliquely inwardly and toward each other and terminating in channel-forming portions, and top, bottom and side wall members formed

independently of said face members, and of channel-like form in cross-section, the edges of said channel members and the margins of the face members at the sides and bottom of the sash being interengaged, substantially as described.

5. A hollow sheet-metal sash-frame comprising front and back face members, each struck up from a single sheet of metal, marginal side wall members forming the four outer sides of the sash-frame and rigidly uniting said front and back face members, and a sheet of glass or analogous glazing supported between said face-plates, the inner margins of said face members forming the boundaries of the sash-opening being extended from the outer face plane of the sash obliquely inwardly to, and engaging the respective sides of the glass, and forming in conjunction with the latter a completely-closed hollow sash-frame, substantially as described.

FRANK VOIGTMANN.
